(57) **CLAIM**

The ornamental design for a golf brush as shown and described.

DESCRIPTION

FIG. 1 is a front, left, and top perspective view of a golf brush, showing my new design;

FIG. 2 is a rear, right, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a detailed view taken from the encircled portion labeled "9" in FIG. 2; and,

FIG. 10 is an exploded view of the golf brush.

The short-dash and long-dash broken lines in FIGS. 2 and 9 denote the boundaries of the detail areas and form no part of the claimed design. The evenly-dashed broken lines in the drawings depict portions of the golf brush that form no part of the claimed design.
